LUIS DE FLOREZ, OF POMFRET, CONNECTICUT, AND WALTER J. MITCHELL, OF FALL RIVER, MASSACHUSETTS.

HEATER FOR DISCHARGE OUTLETS OF FLUID CONTAINERS.

Application filed April 13, 1923. Serial No. 631,887.

This invention relates to containers for viscous fluid and resides particularly in means for facilitating the flow of the fluid from the containers.

5 The invention is particularly applicable to oil tank cars and, while the invention is not limited to this use, it will be described in connection with the same by way of illustration.

10 In the drawing—

The figure is a sectional view showing the device applied to a tank car, only the lower portion of the wall of the tank being shown.

The ordinary tank car includes a discharge 15 pipe for the oil, the discharge from which pipe is controlled by a valve. The invention is illustrated in connection with such a car in which is provided a tank 1 (the bottom only of which is shown in the drawing) having a discharge pipe 2 and a valve 3 which 20 seats in the upper end of the pipe and controls the flow of oil from the tank.

A coupling 4 is secured to the lower end of the pipe and from this coupling a discharge 25 pipe 5 extends. This coupling is provided with a thread 6 of such character that the coupling may be attached to the thread on the lower end of the pipe 2 of the tank cars now in commercial use.

30 In order that the discharge pipe may be heated so that the unseating of the valve 3 and the flow of the oil from the tank will be facilitated, the pipe 2 is provided with a heater.

35 In the illustrated form this heater includes an elongated shell 7 which is adapted to extend longitudinally of and within the pipe 2. This shell is carried by the coupling 4 and is adjustable with relation thereto through a 40 stuffing box 8 which prevents the leakage of the oil being discharged.

An injector 9 extends into the shell 7 and has a discharge opening located preferably 45 near the upper end of the shell. This injector is adapted to convey a heat exchange medium, such as steam, into the shell.

The lower end of the shell 7 is provided with a valve 10 through which the heat exchange medium is discharged.

50 When steam is used as the heat exchange medium the pressure within the shell 7 is controllable by the valve 10 which may be opened to various degrees. This variation of pressure makes it possible to control the

temperature of the shell and vary it to the 55 particular conditions existing.

In operation, the mechanism being assembled in connection with the fluid tank, the temperature of the shell 7 is raised by the injection of the heat exchange medium into 60 the same through the injector 9. This in turn heats the pipe 2 and the valve 3 and its seat.

The heating of the valve greatly facilitates the raising of the same since it melts 65 any ice which may have formed around the valve from the water which usually gravitates to the valve from the oil, and since it reduces the viscosity of the adjacent oil. When the valve is raised the heat penetrates 70 the oil in the tank so that the oil adjacent the discharge opening readily flows from the tank. Furthermore the heating of the pipe 2 insures the continued flow and rapid discharge of the oil, due to the fact that the relatively high temperature of the oil is maintained and consequently its viscosity reduced.

As has been stated, the coupling 4 is adapted to be attached to the discharge pipes 80 of tank cars now in commercial use. As these pipes vary in length the adjustability of the shell 7 makes it possible to adapt the attachment to the various pipes, and still maintain the upper end of the shell adjacent 85 the upper end of the discharge pipe 2 and the valve 3.

While the invention has been described in connection with an oil tank car, it is to be understood that its use is not limited to this, 90 as it may be used in connection with many other containers for viscous fluids. Moreover, the invention is not limited to the particular construction illustrated as many changes may be made therein within the 95 scope of the claims.

We claim:

1. The combination with a fluid tank having a discharge pipe and means controlling the discharge from said tank, of a shell 100 connected with said discharge pipe and adjustable therein and provided with an outlet, and means for injecting a heat exchange medium into said shell.

2. The combination with a fluid tank having a discharge pipe and a valve normally closing the upper end of said pipe, of a shell within said discharge pipe having the 105

upper end thereof spaced from said valve, means for connecting said discharge pipe and shell to permit adjustment of the latter in said discharge pipe, and means for injecting a heat exchange medium into said shell.

3. The combination with a fluid tank having a discharge pipe, of a coupling attached to the end of said pipe, a shell adjustably carried by said coupling and extending into the pipe, and means for injecting a heat exchange medium into said shell.

4. An attachment for a fluid container having a discharge pipe and a control valve therefor, comprising a threaded coupling, a shell adjustably carried by the coupling, and a heat exchange medium injector extending into the shell, said shell being adapted to heat the zone adjacent the control valve for the discharge pipe.

5. In a fluid tank having a discharge pipe

and a valve for controlling the discharge from said tank through said pipe, means for heating said discharge pipe and said valve comprising a shell positioned in said discharge pipe and having an outlet, and means for injecting a heat exchange medium into said shell.

6. In a fluid tank having a discharge pipe and a valve for controlling the discharge from said tank through said pipe, means for heating said discharge pipe and said valve comprising a shell adjustably positioned in said discharge pipe and having an outlet, and means for injecting a heat exchange medium into said shell.

In testimony whereof, we have signed our names to this specification this 2 day of April, 1923.

LUIS DE FLOREZ.
WALTER J. MITCHELL.
